UNITED STATES PATENT OFFICE

WILLIAM M. THOMAS, OF ALBUQUERQUE, NEW MEXICO

CARBURETOR

Application filed April 18, 1931. Serial No. 531,177.

This invention relates to an improvement in devices for mixing a gas and a liquid and particularly to the class of these devices known as carburetors which are used to supply an explosive mixture to an internal combustion engine.

This device employs the conventional float chamber for supplying liquid under a constant head. An air passage is formed adjacent the float chamber and nozzles connected to the float chamber project into this passage to supply fuel therefrom to the gas flowing through the passage. As is customary, the nozzles terminate at a height sufficient to prevent the fuel from the float chamber from flowing through them except when suction is applied to them by the flowing of air through the passage.

Obviously, this passage must be so formed as to produce a suction at the ends of the nozzles when air is flowed through it. The usual way to do this is by forming a constriction around the nozzles as is done in carburetors known as the "Venturi" type. There are several objections to this type of carburetor mainly owing to the resistance offered to the passage of the gas, which prevents the internal combustion engine from sucking a large charge through the carburetor quickly, when desired. There is also an objection based on the fact that the mixture supplied by such a carburetor is not properly proportioned for all speeds and conditions of normal engine operation.

This invention has for its object an improved mixing device which overcomes these objections. This device produces a suction at the ends of the nozzles by a means different from that of the "Venturi" carburetor while it does not offer the same resistance to the flow of gas therethrough, and yet provides a means for properly proportioning the mixture at all times.

This invention comprises a carburetor of the usual form in so far as float chamber, nozzles, choke valve and throttle valve are concerned, but the passage at the point at which the mixing takes place is new and different and the nozzle sizes are adjusted to function with this improved form.

The gas passage through the new carburetor comprises a horizontal and a vertical portion and the nozzles terminate in the lower end of the vertical passage. The vertical portion of the main passage is practically of uniform diameter, but just above the ends of the nozzles and extending above them a short distance into the vertical passage is a cylindrical tube supported from the wall of the vertical passage.

A space between this cylinder and the wall of the vertical passage provides one passageway for gas while the cylinder provides a second. By properly proportioning these, the amount of gas to be by-passed around the liquid or fuel nozzles may be apportioned as desired.

The cylinder, instead of having the ends cut straight across, has each end cut in the shape of one turn of a helix with the ends of each turn connected by an approximately vertical line. The pitch of the helix at the upper end is steeper than of the one at the lower end. The air striking the lower end as it comes in from the horizontal passage is given a swirling or helical motion as it is drawn into the cylinder and thus applies a suction to the nozzles and causes a mixing of the atomized fuel, gas and vapor as it leaves the cylinder.

The cylinder is preferably of slightly smaller inside diameter at a point a short distance above the bottom end and tapers outwardly towards both ends. The taper is necessarily sharper towards the bottom in order that it may reach the outer circumference of the cylinder at the bottom of the cylinder. The cylinder is preferably supported in the main passage by laterally extending lugs engaging notches in the passage wall but may be supported in any other desired manner.

In a modification which is especially satisfactory, the cylinder is offset slightly from the center of the main passage towards one side. This alters the shape of the surrounding or by-pass passage and in many instances improves the results obtained. Also, the rear half of this surrounding passage may be closed, that is only a half circle of passage

provided. This half circle of passage is preferably on the side of the cylinder from which the incoming gas approaches. With the cylinder set off-center this passage is wider toward one side edge thereof and becomes narrower as the passage extends around the cylinder.

For specific illustrations of the preferred embodiments of the applicant's invention, 10 reference may be had to the accompanying drawing, in which;

Figure 1 is a side elevation, partly in section.

Figure 2 is a partial plan view with the 15 top half of the carburetor removed to show the cylinder in place.

Figure 3 is a perspective of the inside cylinder.

Figure 4 is a side view of the inside cylinder. 20

Figure 5 is a partial section in side elevation showing a modified form of this invention, and

Figure 6 is a top view of the cylinder of 25 the modification shown in Figure 5.

Referring to Figures 1 to 4 the reference character 1 designates a casting forming the lower part of the carburetor and 2, a casting forming the upper part of the carburetor. 30 These two castings enclose a float chamber, not shown, and form a passage made up of a horizontal section 3 and a vertical section 4, shown in section in Figure 1. Gas is adapted to flow into the passage 3 and its 35 flow may be controlled when desired by a choke valve 5 located near the entrance of the passage 3. Gas entering the passage 3 passes therethrough and upwardly into and through passage 4, and thence to the manifold of an 40 internal combustion engine. A butterfly valve 6 controls the flow of gas from the passage 4.

In the passage 4 at its lower end is located a cylinder 10 of smaller outside diameter than 45 the inside of the passage 4 and supported in the passage 4 by radially extending lugs 11 extending into notches 12 in the walls of the passage 4. The cylinder 10 is hollow and open at both ends. The outside is cylindrical 50 in form and the ends thereof are each cut in the shape of one turn of a helix with the ends thereof joined. The pitch of the helix forming the top of the cylinder is considerably greater than the pitch of the helix forming 55 the bottom of the cylinder. The inside of the cylinder has a constricted portion 13 a short distance above the lower edge of the cylinder and the inside of the cylinder tapers outwardly to meet the outside of the cylinder 60 at both ends. This taper is sharper towards the bottom end of the cylinder on account of the shorter distance from the constricted portion to the bottom end. Except for the pitch the helix forming the bottom and the helix 65 forming the top of the cylinder are the same,

that is, they progress in the same direction. Each end appears as one turn of a helix with the ends thereof joined by a substantially vertical line. This vertical line is on one side 70 for the bottom and on the other side for the top end of the cylinder. The portion which extends farthest downward is located away from the side from which the gas enters from the passage 3.

Nozzles are provided as indicated at 20 and 75 21 for supplying fuel to the gas. These nozzles extend upwardly from the bottom of the passage 3 in the casting 1 and terminates slightly below the cylinder 10. These nozzles 80 are supplied by the fuel from a float chamber which is not shown.

The conventional parts of the carburetor such as the float chamber, choke valve and mixture regulating mechanism 25, the idler nozzle 26 and the gasoline inlet 27, need not 85 be described in detail as they are well known in the art.

In the embodiment shown in Figures 5 and 6 the cylinder 10 is replaced by a similar cylinder 30 having a constricted portion 33, but this cylinder is supported in the passage 4 by a ring 31 adapted to be held in place by a groove 32 in the wall of the passage. The cylinder 30 is set eccentrically towards one side in the ring and only a half of the space 90 between the cylinder and ring is left open. The half of this space which lies on the side farthest from the intake is sealed as shown at 34, leaving only a semi-circular opening 35 which is wider at the side edge 36 than at the side edge 34. The rest of the construction 95 of this modification is the same as that of the previously described embodiment and hence it 100 will not be described in detail.

The operation of the device is as follows: 105

The air or other gas entering through the passage 3 passes upwardly around the nozzles 20 and 21 and a part thereof through the cylinder 10. Upon striking the helically formed edge of the cylinder 10 this air is given a spiral or helical motion and passing through the cylinder 10 past the constriction 110 115 120 125 130 135 140 145 150 the cylinder may be so proportioned as to cause a proper mixture to be supplied to the internal combustion engine at all speeds and due to the large openings through which the 5 gas flows there is relatively little resistance offered to the inflowing gas by this carburetor. This permits the engine to get a maximum charge whenever the throttle valve is opened and materially aids in engine efficiency. The carburetor contains no moving parts in the mixing chamber and hence is sturdy and does not easily get out of order.

In the modification shown in Figures 5 and 15 6, the action of the cylinder is similar to that in the first-mentioned embodiment and the by-pass opening 35 because of its particular shape causes better mixing.

It will be understood that the embodiments above described merely illustrate some of the 20 preferred forms of this invention, which is limited only as indicated by the appended claims.

I claim:

1. In a carburetor, a main passage, a hollow 25 open ended cylinder suspended in said main passage substantially axially parallel thereto, the ends of said cylinder each being in the form of one turn of a helix with the ends thereof joined, said cylinder being of 30 smaller inside diameter at a point between the ends but nearer one end thereof and tapering outwardly toward both ends.

2. In a carburetor, a main passage, a hollow 25 open ended cylinder suspended in said main passage substantially axially parallel thereto, the ends of said cylinder each being in the form of one turn of a helix with the ends thereof joined, the pitch of the helix on one end being greater than on the other.

40 3. In a carburetor, a main passage, a hollow 25 open ended cylinder suspended in said main passage substantially axially parallel thereto, the ends of said cylinder each being in the form of one turn of a helix with the ends thereof joined, the pitch of the helix on one end being greater than on the other, said cylinder being of smaller inside diameter at a point between the ends thereof than at said ends, and means to supply fuel to gas 50 flowing through said cylinder.

45 4. In a carburetor, a main passage comprising a horizontal and a vertical portion through which gas is adapted to flow, a hollow 55 open ended cylinder suspended in said vertical portion substantially axially parallel thereto and near the horizontal portion, the ends of said cylinder each being in the form of one turn of a helix with the ends thereof joined, the pitch of the helix on one 60 end being greater than on the other, said cylinder being of smaller inside diameter at a point between the ends thereof than at said ends, and means to supply fuel to gas flowing through said cylinder.

65 5. In a carburetor having a main passage

comprising a horizontal portion through which a gas is adapted to enter, and a vertical portion extending upward therefrom, in which fuel is adapted to be mixed with the gas and the mixture delivered therefrom, a 70 hollow open ended cylinder of smaller diameter than said vertical passage suspended axially parallel, but offset to one side, in the lower end of said vertical passage, the ends of said cylinder each being in the form of one 75 turn of a helix with the ends joined, and means to supply fuel to the gas flowing through said cylinder.

6. In a carburetor having a main passage comprising a horizontal portion through which a gas is adapted to enter, and a vertical portion extending upward therefrom, in which fuel is adapted to be mixed with the gas and the mixture delivered therefrom, a 80 hollow open ended cylinder of smaller diameter than said vertical passage suspended axially parallel to and in the lower end of 85 said vertical passage, the ends of said cylinder each being in the form of one turn of a helix with the ends joined, the cylinder being so formed that part farthest from the intake end of the horizontal passage extends farther downward than that nearest said intake and said cylinder being of smaller inside 90 diameter at a point near the lower end and tapering outwardly towards both the top and bottom.

7. In a carburetor having a main passage comprising a horizontal portion through which a gas is adapted to enter, and a vertical portion extending upward therefrom, in which fuel is adapted to be mixed with the gas and the mixture delivered therefrom, a 100 hollow open ended cylinder of smaller diameter than said vertical passage suspended axially parallel, but offset to one side, in the lower end of said vertical passage, the ends of said cylinder each being in the form of one 105 turn of a helix with the ends joined, means to close a part of the passage formed between said cylinder and passage.

8. In a carburetor having a main passage comprising a horizontal portion through which a gas is adapted to enter, and a vertical portion extending upward therefrom, in which fuel is adapted to be mixed with the gas and the mixture delivered therefrom, a 110 hollow open ended cylinder of smaller diameter than said vertical passage suspended axially parallel, but offset to one side, in the lower end of said vertical passage, the ends of said cylinder each being in the form of one 115 turn of a helix with the ends joined, means to close substantially half of the passage formed between said cylinder and passage.

In testimony whereof I affix my signature.

WILLIAM M. THOMAS.
